UNITED STATES PATENT OFFICE

ARTHUR ANDERSON, OF NEWTON CENTER, AND FRITZ W. A. HENRICI, OF BOSTON,
MASSACHUSETTS

LATCH

Application filed November 10, 1925. Serial No. 68,195.

This invention relates to latches and particularly to latches for washing machine cylinder covers and the like, and its object is to provide an improved latch having, among others, 5 the advantages hereinafter pointed out.

Referring to the drawing of one embodiment of my invention selected for illustration and description herein,

Fig. 1 shows a washing machine having 10 its cylinder cover equipped with my novel latch;

Fig. 2, a front view of the latch removed from the cover;

Fig. 3, a vertical section on the line 3—3, 15 Fig. 2;

Fig. 4, a longitudinal sectional view looking up on the line 4—4, Fig. 2;

Fig. 5, a front view showing a bolt of different type; and

20 Fig. 6, a front view showing the latch in unlocked position.

Referring first to Figs. 1, 2 and 3, my novel construction comprises the usual cylinder 1, the cover 2 of which is adapted to slide 25 upwardly beneath curved guides 3, 3, and top 4 of the washing machine casing 5.

At any convenient point or points, and herein near the lower opposite corners of the cover 2, it is provided with a novel latch comprising a housing 6 with bosses 7 threaded to receive screws for securing the housing to the inner face of the cover 2, one casing cover 2^a being shown open.

The end wall 8 of the housing adjacent 35 the cover edge is cut away to permit the bolt 9 to slide therethrough. This bolt has a laterally extended and widened section or plate 10 within the housing which carries threaded or otherwise secured thereto an arm 40 or extension 11 which is substantially a part of the bolt. The bolt is provided with any suitable pressure exerting or throwing member as a spring 12 for normally throwing the bolt outwardly. The spring is seated against the web 14 on the rear housing wall at one end, and against the plate 10 at the opposite end. This arm 11 slides through an aperture 13 in the guide web 14. The opposite housing end wall 144 is apertured at 145 to permit convenient assembly of the arm and spring.

For withdrawing the bolt, or unlocking the latch, Figs. 2, 4 and 6, we have provided a novel detached and pressure supported handle 15 provided at its bolt operating end with oppositely positioned and laterally extended arms 16, 16, which are in this case relatively thin and lie between the plate 10 and the housing wall 8, straddling the bolt 9, one at the top and one at the bottom thereof.

The handle 15 normally lies substantially in the longitudinal, central plane of the housing and is operable entirely therein, preferably not extending outwardly beyond the cover, thereby obviating any danger to the person or garments of the operator from the protruding handle when the cover is raised or lowered, the cover 2 being provided with a slot 17 to permit the fingers to be inserted beneath or above the handle. It will be noticed that the handle is not pivoted or fastened to the housing or bolt, but is pressure positioned and double fulcrumed in action.

When one desires to raise the cover, the operator places his fingers beneath the handle, presses upward on it and this causes the handle to swing upwardly about the upper arm edge 18 as a fulcrum, with the lower arm swinging inwardly against the lower edge of the plate 10 pushing it inwardly, withdrawing the bolt 9 from the socket 19. The arm edge 18 contacting with the plate 10 gives it a relatively long throw inwardly, releasing the bolt 9 quickly. Continued pressure on the handle will of course raise the cover to its upward position.

Thus it will be seen, that by simply pressing upon the hand slightly at first, one releases the latch, and increased pressure raises the cover without the necessity of changing the direction of pressure or releasing the handle. To lower the cover, one naturally presses downwardly on the handle, thus first releasing the bolt from its socket and then causing the cover to slide downwardly; but it will be noticed that the handle may be pressed either upwardly or downwardly, either movement of the handle acting to release the bolt, one handle member only being provided.

Our novel construction is simple, easy to install, readily operative and most conven-

ient, the movement that operates the latch serving also when continued, to operate the cover or door.

Our invention is not restricted to the particular embodiment described and illustrated herein, and we claim:

A latch comprising a housing, a bolt entirely operable therein, a pressure plate for the bolt, a throwing member seated thereon, and a resiliently supported handle operative against the plate either above or below the bolt for operating the bolt.

In testimony whereof, we have signed our names to this specification.

ARTHUR ANDERSON.
FRITZ W. A. HENRICI.
